(57) **CLAIM**

The ornamental design for a production digital printer, as shown and described.

DESCRIPTION

FIG. 1 is a perspective view of a production digital printer in accordance with the present invention;
FIG. 2 is a front view thereof;
FIG. 3 is a right side view thereof;
FIG. 4 is a rear view thereof;
FIG. 5 is a left side view thereof;
FIG. 6 is a top plan view thereof; and,
FIG. 7 is a bottom plan view thereof.

The broken lines shown in the views are included for the purpose of illustrating portions of the production digital printer that form no part of the claimed design.

The xerox logo forming part of the disclosure is a registered trademark of Xerox Corporation.
